WINDOW LOCK

Frank E. Pavelka, San Antonio, Tex.

Application March 28, 1935, Serial No. 13,537

1 Claim. (Cl. 292—54)

This invention relates to window locks. The primary object of the present invention is to provide a window lock that is adapted for installation on vertically sliding window sashes, that is easily applied to the window sashes, that is comparatively inexpensive to manufacture, and thoroughly efficient to prevent one sash from being raised with respect to the other sash when in the locked position.

With the foregoing and other objects in view the invention consists of a novel construction, combination and arrangement of parts as will be hereinafter more specifically described and illustrated in the accompanying drawing wherein is disclosed an embodiment of the invention, but it is to be understood that changes, variations and modifications may be resorted to without departing from the spirit of the claim hereunto appended.

In the drawing wherein like reference characters denote corresponding parts throughout the several views:

Figure 1 is a fragmentary sectional view through the upper and lower window sashes showing an adaptation therewith of the window lock in accordance with the present invention.

Figure 2 is a horizontal section through the upper portion of the hood showing the underlying parts of the lock in plan view and in the locked relation.

Figure 3 is a vertical section taken substantially on line 3—3 of Figure 2 and looking in the direction of the arrows.

Referring to the drawing in detail, A indicates a window frame, and B and C indicate respectively the upper and lower sashes of the window sliding vertically in the frame A. Secured to the upper face of the lower rail 5 of the upper window sash B is a rectangular keeper plate 6. Rising above the keeper plate 6 is a centrally apertured keeper knob a the periphery of which slopes outwardly from the top to the bottom thereof to provide a cam periphery 7 of frusto-conical configuration. A screw 8 extends through the aperture in the knob and is anchored at its inner end to the keeper plate 6 thereby securing the knob a to the plate. Where the lower face of the keeper knob joins the plate 6 there is an annular groove 9 in the knob to receive the projecting ends of the latch levers as will hereafter appear.

On the upper face of the upper rail 10 of lower sash C there is a latch plate 11 secured thereto by screws 12. A pair of latch levers 13, 14 are formed of flat straight bars and are pivoted to

the latch plate 11 intermediate their ends by the stud screws 15, 16 and the lower ends of these screws are connected with the plate 11. The latch levers 13, 14 rock on the pivot screws 15, 16 in a horizontal plane and the outer ends of these latch levers extend outwardly from the lower sash C in the path of the upper sash B thereby forming gripping jaws which have arcuate recesses 13a and 14a on confronting side edges near their outer ends that engage the opposite sides of the knob a and seat in the annular groove 9 when this groove is brought into registry with the plane of the levers. Outwardly of the pivots 15, 16 there is a coil spring 17 connected at its opposite ends to the levers 13, 14 as 15 at 18, 19. This spring 17 bridges the space between the latch levers 13, 14 and holds them in locked relation in the annular groove 9 on the knob.

A rectangular hood 20 is open at its bottom as 20 will appear in Figures 2 and 3 of the drawing with the outer portion thereof overhanging the path of the upper window sash B. On the inner end of the hood 20 is formed the lateral flanges 21, by which the hood is secured to the upper 25 face of latch plate 11 by the screws 22. The top wall 23 of the hood 20 forms a cover for the keeper knob a and the major length of the latch levers 13, 14, while the rear ends of the latch levers extend through a slot or cavity 24 in the 30 hood. On the projecting inner ends of the latch levers 13, 14 are upstanding vertical gripping fingers 25 which serve to release the levers from locked relation when the said fingers are pressed together. Inside the hood 20 there is a central 35 limit stop in the form of a peg 26 secured to the plate 11 between the confronting ends of latch levers 13, 14. On the outside of each lever 13, 14 is an upstanding peg 27 which serves to limit the space between the outer ends of the levers 40 when they are closed under the tension of spring 17 while the central peg 26 limits the width to which the outer end of the latch levers may be opened. Pegs 27 retain the outer ends of the latch levers in spaced relation so that the width 45 between these levers will be such as to engage the cam periphery 7 and be urged apart thereby when either window sash is moved from open to closed position.

Having thus described the invention, what is 50 claimed as new is:

A window lock comprising a keeper plate adapted to be secured to the lower rail of an upper window sash, a frusto-conical keeper knob secured to the plate and formed with a continuous 55

peripheral groove near the base thereof, a latch plate adapted to be secured to the upper rail of the lower window sash, a pair of elongated straight flat latch levers mounted in side by side relation and formed with arcuate recesses on confronting sides near the outer ends thereof, pivot studs connecting intermediate portions of the levers to the latch plate to swing in a horizontal plane with the outer ends of the latch levers projecting in the path of the upper sash, a spring connected at its opposite ends to the levers outwardly of the pivot studs to urge them together in locked relation with the recessed edge of the levers seated in the groove on the knob, the inner ends of the levers formed with upstanding gripping fingers to rock the latch levers and re-

lease them from the groove and the knob, a single abutment peg anchored to the latch plate inwardly of the pivot studs and between the inner ends of the latch levers to limit the space between the ends of the levers in open position, and a pair of abutment pegs anchored to the latch plate one to the outside of each of the levers and outwardly of the pivot studs to hold the outer ends of the levers in spaced relation when disengaged with the keeper knob so that the levers will be forced apart when the window is moved from open to closed position whereupon the frustum of the keeper knob enters the space between the levers. 5 10 15
